UNITED STATES PATENT OFFICE

2,565,711

PUSH-BUTTON ACTUATED DOOR LATCH

Albert G. Whalley, Toronto, Ontario, Canada, assignor of one-half to Clifton William Hocking, Toronto, Ontario, Canada

Application September 30, 1948, Serial No. 51,940

9 Claims. (Cl. 292—181)

1

This invention relates to door latches, and more particularly to push-button actuated door latches.

An object of this invention is to provide a door latch which may be released by suitable push-buttons located directly opposite each other on each side of the door.

Another object of this invention is to provide a door latch having actuating and latching bolts which are reliable in operation and which are easily manufactured.

A further object of this invention is to provide an automatic door latch, in which the bolts are so constructed that they may be reversed thereby enabling the latch to be installed in either right hand or left hand doors.

All of the foregoing and still further objects and advantages of the invention will become apparent from a study of the following specification, taken in conjunction with the accompanying drawings, wherein like characters of reference indicate corresponding parts throughout the several views and wherein:

Fig. 1 is a side elevation of a door latch constructed according to this invention, the parts being shown in the positions which they will normally assume when the door is open;

Fig. 2 is a side elevation of the door latch showing the parts as they would appear when the door is almost closed but before the latching bolt has slipped into its retaining slot in the door jamb;

Fig. 3 is a side elevation of the door latch showing the parts as they would appear when the door is closed and latched;

Fig. 4 is a side elevation of the door latch showing the parts as they would normally appear after the actuating lever has been released by means of pressure applied to one of the push-buttons, which allows the latching bolt to retract and permits the door to open;

Fig. 5 is a vertical sectional view taken on the line 5—5 of Fig. 1;

Fig. 6 is a vertical sectional view taken on the line 6—6 of Fig. 4;

Fig. 7 is a vertical sectional view taken on the line 6—6 of Fig. 4 showing particularly the construction which enables the latching bolt bar to be released when pressure is applied to the auxiliary push-button;

Fig. 8 is a vertical sectional view taken on the line 3—8 of Fig. 3;

Fig. 9 is a vertical sectional view taken on the line 9—9 of Fig. 3;

Fig. 10 is a perspective view of the actuating bolt;

2

Fig. 11 is an end view of the actuating bolt; Fig. 12 is a perspective view of the latching bolt; and

Fig. 13 is an end view of the latching bolt.

- 5 The invention disclosed and claimed herein is believed to be a considerable advance over prior art push-button actuated door latches, and reference is made particularly to Harold Keats Patent No. 2,188,642, dated January 30, 1940 which discloses a representative prior art construction. In the Keats' device, the actuating lever whereby the latching bolt and the actuating bolt are operatively connected rocks on one fulcrum only, and in order to provide a mechanism whereby 10 the door may be opened from either side by pressing a push-button, it is imperative that one push-button be below the fulcrum and that the other push-button be above the fulcrum; thus the push-buttons cannot be opposite one another. 15 This increases manufacturing costs, since identical escutcheon plates cannot be provided for both sides of the door and it is necessary instead to provide two different escutcheon plates having push-buttons located in different positions.
- 20 It is also characteristic of prior art devices that the bolts are spring loaded by means of tension springs connected to pins on the bolt and on the supporting structure. In accordance with this invention the spring loading of the bolts is provided by compression springs inserted in 25 elongated apertures in the bolts, one end of a spring engaging an end of the aperture and the other end engaging a pillar extending from the supporting structure and passing through the said aperture.
- 30 35 According to this invention an actuating bolt 10 is slidably mounted on flanged frame 11 and is adapted to slide longitudinally therein between the guide pillars 12 which extend from the frame. A latching bolt 13 is also mounted on frame 9, and it is likewise adapted to slide longitudinally 40 therein between another pair of guide pillars 14. Bolts 10 and 13 respectively have slots 15 and 16 cut therein and within these slots extend columns 17 and 18 which are fixed to the frame. 45 Actuating bolt 10 is urged outwardly by means of compression spring 19 which is mounted in slot 15 and extends between the leading end of the said slot and one side of column 17. Similarly latching bolt 13 is urged inwardly by means 50 of compression spring 20 which is mounted in slot 16 and extends between the trailing end of the said latching bolt and one side of column 18. A ridge 21 is provided on the frame approximately midway between bolts 10 and 13 and parallel thereto near the trailing ends of the bolts.

Ridge 21 provides a fulcrum at one side of actuating lever 22 which extends between the two bolts, the particular construction of the said actuating lever being subsequently described in detail.

Journal pin 23 extends from ridge 21 transversely thereto and passes through a slot 24 provided in actuating lever 22. A disc-like projection 25 on one end of lever 22 extends within a recess 26 provided in the lower edge and back face of the actuating bolt 10. Projection 25 is disc-shaped so that it may both slide and rotate within recess 26 when actuating bolt 10 is forced inwardly against the force of helical spring 19, this inward movement of actuating bolt 10 causing rotation of actuating lever 22 about journal pin 23. A projection 27 on the lower end of lever 22 is adapted to engage the front edge 28 of a recess 29 provided in latching bolt 13 in its front face at its upper rearward end. A helical spring 30 is connected at one end to a pin 31 extending from the frame, and its other end is connected to actuating lever 22 thus urging the projection 27 of the actuating lever against the edge 28 of recess 29 provided in latching bolt 13.

A face plate 32 is secured to frame 11 by a screw 33 which is threaded into a column 34 extending from the frame; there is thus provided a closed chamber within which is enclosed the aforescribed mechanism.

Openings 35 and 36 are provided in frame 11 and face plate 32 respectively at points therein opposite the actuating lever 22; it should be noted that these openings are also opposite each other. Through these openings extend push rods 37 and 38 respectively which are adapted to register with and be actuated by suitable push-buttons (not shown) provided in escutcheon plates mounted on either side of the door. A satisfactory type of escutcheon plate with push-button which may be used with this invention is disclosed in Patent No. 2,314,646 to Harold Beatson Keats, issued March 23, 1943.

The various stages of operation of the door latch will now be described in detail. For the satisfactory operation of this latch it is necessary that the door jamb be provided with a bearing plate 40 which includes a plane surface with which may engage the actuating bolt 10, and a recess 41 into which the latching bolt 13 may enter.

When the door is gradually moved from an open to a closed position, the actuating bolt 10 engaging with the plane surface of the bearing plate on the door jamb will be gradually pushed inwardly, thereby causing actuating lever 22 to pivot at its projection 27 against the edge 28 of recess 29 provided in latching bolt 13, as shown in Fig. 2; the movement of actuating lever 22 during this operation is guided by journal pin 23 extending through elongated slot 24 provided in the actuating lever.

As soon as the door is completely closed, the front end of the latching bolt will register with the recess 41 provided in the bearing plate 40 secured to the door jamb, and the latching bolt will suddenly be urged forwardly by the combined negative action of compression spring 20 and positive action of tension spring 30 which is urging the latching lever 22 forwardly so as to in turn urge the latching bolt forwardly. Thus the door will be securely latched by the engagement of latching bolt 13 in the recess provided in the bearing plate of the door jamb. Although helical spring 20 has a negative action in that it

urges the latching bolt rearwardly, tension spring 30 more than overcomes the force of the said compression spring 20 since tension spring 30 is selected to have a spring constant greater than the spring constant of spring 20.

Referring now to Fig. 5, a compression spring 42 which is coiled around a pin 43 extending from the face plate 32 has one end bearing against the said face plate and the opposite end bearing against actuating lever 22. Thus the said compression spring tends to fulcrum the actuating lever about ridge 21, thus causing projection 27 to press downwardly at all times upon the surface of latching bolt 13 at recess 29.

The latch may be released when it is desired to open the door by pressing the push-button which engages push rod 37 or 38, depending of course on the "side" from which the door is being opened. The action of the latch when push rod 37 is pressed will first be described. Depression of the push rod 37 causes actuating lever 22 to fulcrum about ridge 21 as shown in Fig. 6; spring 42 is thereby compressed and projection 27 will rise out of recess 29 in latching bolt 13 and will clear the leading edge 28 of the said recess, and compression spring 20 will immediately thereafter cause the latching bolt to be withdrawn to the position shown in Fig. 4. A shallow recess 29a which is a continuation of recess 29 provides clearance for the projection 27 when the latching bolt is in this withdrawn position. When the latching bolt is withdrawn, it no longer engages with the recess provided in the bearing plate of the door jamb and the door may then be opened.

As soon as the door is opened, spring 19 will urge the actuating bolt forwardly into the position shown in Fig. 1, and this in turn causes actuating lever 22 to pivot about journal pin 23 thereby causing the extension 27 of the actuating lever to fall into the recess 29 of the actuating bolt 13, thereby cocking the latch for subsequent use.

If it be assumed that the dimensions of the parts of the mechanism are such that the moment arm of projection 25 about journal pin 23 is equal to the moment arm of the axis of tension of helical spring 30 about journal pin 23, then compression spring 19 need only have a spring constant slightly greater than that of tension spring 30 in order to effect the aforementioned cocking action. Of course, in practice, the co-efficient of friction of the sliding parts is not to be ignored, and hence in the preferred construction spring 19 has a spring constant approximately one-third greater than that of tension spring 30.

The operation of the latch when it is released from "the other side," i. e. by pressing the push button which presses against push rod 38 will now be described. In this operation, actuating lever 22 is not fulcrummed about ridge 21 but its projection 25 actually fulcrums on the surface of recess 26 in actuating bolt 10 as shown in Fig. 7. The fulcrum in this case is thus bearing on one side of actuating lever 22 whereas the ridge 21 in the other case was providing a fulcrum on the opposite side of the actuating lever. Spring 42 is thus compressed and projection 27 will rise out of recess 29 in latching bolt 13 and will clear the leading edge 28 of the said recess. The compression spring 20 will immediately thereafter cause the latching bolt to be withdrawn to the position shown in Fig. 4, allowing the door to be opened.

It will be noted that the construction of the actuating lever 22 whereby it may fulcrum about two different points, namely about ridge 21 when push rod 37 is pressed, and about the surface of actuating bolt 10 at recess 26 when push rod 28 is pressed, enables the two push rods to be located opposite each other. This of course presents a great advantage in that the escutcheon plates for opposite sides of the door may be identical and it is not necessary for each door to provide two escutcheon plates having push-buttons located in different positions.

In order that the latch may be installed in both right hand and left hand doors by simply reversing the two bolts, there is provided in actuating bolt 10 a "reverse" means 44 corresponding to recess 26, and there are provided in latching bolt 13 reverse recesses 45 and 45^a corresponding to recesses 29 and 29^a respectively.

It is thought that the construction and use of the invention will be apparent from the above description of the various parts and their purpose. It is to be understood that the form of the invention herewith shown and described is to be taken as a preferred example of the same and that various changes in the shape, size and arrangement of parts may be resorted to, without departing from the spirit of the invention or the scope of the subjoined claims.

What I claim as my invention is:

1. A latch of the class described, comprising a support, an actuating bolt and a latching bolt projectable from the same edge of and mounted on said support, means continuously tending to project said actuating bolt, means continuously tending to retract said latching bolt, an actuating lever pivoted on said support for operatively connecting said bolts together whereby as said actuating bolt is pushed back said latching bolt may be projected, a fulcrum at one side of the actuating lever and about which the actuating lever may be rocked, push means extending through the support opposite the other side of the actuating lever and adapted when pressed to move the actuating lever to rock it about the said fulcrum to break the operative connection between the two bolts and allow the projected latching bolt to retract, a fulcrum at the other side of the actuating lever spaced from the aforementioned fulcrum and about which the actuating lever may be rocked, push means extending through the support opposite the first mentioned side of the actuating lever and adapted when pressed to also move the actuating lever to rock it about the second mentioned fulcrum to break the operative connection between the two bolts and allow the latching bolt to retract, the provision of the two fulcrums as aforesaid enabling the two push means on opposite sides of the actuating lever to be disposed co-axially.

2. A latch of the class described, comprising a support, an actuating bolt and a latching bolt projectable from the same edge of and mounted on said support, means continuously tending to project said actuating bolt, means continuously tending to retract said latching bolt, an actuating lever pivoted on said support for operatively connecting said bolts together whereby as said actuating bolt is pushed back said latching bolt may be projected, a fulcrum at one side of the actuating lever and about which the actuating lever may be rocked, push means extending through the support opposite the other side of the actuating lever and adapted when pressed to engage the said other side of the actuating

lever to rock it about the said fulcrum to break the operative connection between the two bolts and allow the projected latching bolt to retract, a fulcrum at the said other side of the actuating lever spaced from the aforementioned fulcrum and about which the actuating lever may be rocked, push means extending through the support opposite the first mentioned side of the actuating lever and adapted when pressed to engage the said first mentioned side of the actuating lever to rock it about the second mentioned fulcrum to break the operative connection between the two bolts and allow the projected latching bolt to retract, the provision of two fulcrums as aforesaid enabling the two push means on opposite sides of the actuating lever to be disposed co-axially.

3. A latch of the class described comprising a support, an actuating bolt and a latching bolt projectable from the same edge of and mounted on said support, means continuously tending to project said actuating bolt through said edge, means continuously tending to retract said latching bolt from the said edge, a step in the side of the actuating bolt adjacent one face of the support, a step in the side of the latching bolt adjacent the other face of the support, an actuating lever pivoted on said support and engaging at its opposite ends the steps in the two bolts, the said actuating lever thus providing an operative connection between said bolts whereby as said actuating bolt is pushed back said latching bolt may be projected, a fulcrum at one side of the actuating lever on which the lever may be rocked, a fulcrum spaced from the first mentioned fulcrum and at the other side of the actuating lever on which the lever may also be rocked, push means extending through the support opposite one side of the lever and adapted when pressed to engage the lever between the two fulcrums and rock it on one of the fulcrums to cause an end of the lever to be disengaged from the step in a bolt, push means extending through the support opposite the other side of the lever and adapted when pressed to engage the lever between the two fulcrums and rock it on the other of the fulcrums to cause an end of the lever to be disengaged from the step in a bolt, the disengagement of the actuating lever from the step in a bolt caused by pressure on either push means bearing on the lever breaking the operative connection between the two bolts and allowing the projected latching bolt to retract.

4. A latch of the class described comprising a support, an actuating bolt and a latching bolt projectable from the same edge of and mounted on said support, means continuously tending to project said actuating bolt through said edge, means continuously tending to retract said latching bolt from said edge, a step in the side of the actuating bolt adjacent one face of the support, a step in the side of the latching bolt and adjacent the other face of the support, an actuating lever pivoted on said support and engaging at its opposite ends the steps in the two bolts, the said actuating lever thus providing an operative connection between said bolts whereby as said actuating bolt is pushed back said latching bolt may be projected, a spring engaging the actuating lever and tending to turn it about its pivot to urge forwardly the end of the actuating lever which engages the actuating bolt whereby the said end of the latching lever is normally held in contact with the front end of the step.

5. A latch of the class described comprising a support, an actuating bolt and a latching bolt projectable from the same edge of and mounted on said support, a spring continuously tending to project said actuating bolt through said edge, a spring continuously tending to retract said latching bolt from said edge, a step in the side of the actuating bolt adjacent one face of the support, a step in the side of the latching bolt adjacent the other face of the support, an actuating lever pivoted in said support and engaging at opposite ends the step in each of bolts, the said actuating lever thus providing an operative connection between said bolts whereby as the said actuating bolt is pushed back said latching bolt will be projected, a spring engaging the actuating lever and tending to turn it about its pivot to urge forwardly the end of the actuating lever which engages the latching bolt, the said actuating lever spring being unable to overcome the tendency of the actuating bolt spring to project the actuating bolt through the aforesaid edge of the support, a fulcrum at one side of the actuating lever on which the lever may be rocked, a fulcrum spaced from the first mentioned fulcrum and at the other side of the actuating lever on which the lever may also be rocked, push means extending through the support opposite one side of the lever and adapted when pressed to engage the lever between the two fulcrums and rock it on one of the fulcrums to cause an end of the lever to be disengaged from the step in a bolt, push means extending through the support opposite the other side of the lever and adapted when pressed to engage the lever between the two fulcrums and rock it on the other of the fulcrums to cause an end of the lever to be disengaged from the step in a bolt, the disengagement of the actuating lever from the step in a bolt caused by pressure on either push means bearing on the lever breaking the operative connection between the two bolts and allowing the projected latching bolt to retract.

6. A latch of the class described comprising a support, an actuating bolt and a latching bolt projectable from the same edge of and mounted on said support, means continuously tending to project said actuating bolt through said edge, means continuously tending to retract said latching bolt from said edge, a step at the rear end of one of the bolts, a recess at the rear end of the other bolt, an actuating lever pivoted on said support and engaging at its opposite ends the recess and the step in the bolts, the said actuating lever thus providing an operative connection between said bolts whereby as said actuating bolt is pushed back said latching bolt may be projected, a fulcrum at one side of the actuating lever on which the lever may be rocked, a fulcrum spaced from the first mentioned fulcrum and at the other side of the actuating lever on which the lever may also be rocked, push means extending through the support opposite one side of the lever and adapted when pressed to engage the lever between the two fulcrums and rock it on one of the fulcrums to cause an end of the lever to be disengaged from the aforesaid step, push means extending through the support opposite the other side of the lever and adapted when pressed to engage the lever between the two fulcrums and rock it on the other of the fulcrums to cause an end of the lever to be disengaged from the step, the disengagement of the actuating lever from the step caused by pressure on either push means bearing on the lever breaking

the operative connection between the two bolts and allowing the projected latching bolt to retract.

7. A latch of the class described comprising a support, an actuating bolt and a latching bolt projectable from the same edge of and mounted on said support, means continuously tending to project said actuating bolt through said edge, means continuously tending to retract said latching bolt from said edge, a step at the rear end of one of the bolts, a recess at the rear end of the other bolt, an actuating lever pivoted on said support and engaging at its opposite ends the recess and the step in the bolts, the said actuating lever thus providing an operative connection between said bolts whereby as said actuating bolt is pushed back said latching bolt may be projected, a fulcrum on the support on which the side of the actuating lever bears and on which it may be rocked, the recess at the rear end of one of the bolts providing another fulcrum on which the other side of the actuating lever bears and on which it may be rocked, push means extending through the support opposite one side of the lever and adapted when pressed to engage the lever between the two fulcrums and rock it on the fulcrum mounted on the support to cause the end of the lever engaging a step to be disengaged therefrom, push means extending through the support opposite the other side of the lever and adapted when pressed to engage the lever between the two fulcrums and rock it on the fulcrum provided by the aforesaid recess to cause the end of the lever engaging the step to be disengaged therefrom, the disengagement of the actuating lever from the step caused by pressure on either push means bearing on the lever breaking the operative connection between the two bolts and allowing the projected latching bolt to retract.

8. A latch of the class described comprising a support, two spaced apart pillars extending from said support, an actuating bolt having an elongated aperture and mounted for reciprocating movement on the support, one of the pillars extending through the aperture in the actuating bolt, a latching bolt also having an elongated aperture and mounted for reciprocating movement on the support, the other pillar extending through the aperture in the actuating bolt, guides extending from the support and engaging the bolts to control their movement, a compression spring inserted in the aperture of the actuating bolt and having one end bearing against an end of the aperture and the other end bearing against the pillar therein, the said spring continuously tending to project the actuating bolt through an edge of the support, a compression spring inserted in the aperture of the latching bolt and having one end bearing against an end of the said aperture and the other end against the pillar therein, the said spring continuously tending to retract the latching bolt from the aforesaid edge of the support, an actuating lever pivoted on said support for operatively connecting said bolts together whereby as said actuating bolt is pushed back said latching bolt may be projected, push means extending through the support opposite one side of the actuating lever and adapted when pressed to move the actuating lever and break the operative connection between the two bolts and allow the projected latching bolt to retract, push means extending through the support opposite the other side of the actuating lever and adapted when pressed to also

move the actuating lever and break the operative connection between the two bolts and allow the latching bolt to retract, the said push means being located substantially opposite each other.

9. A latch of the class described, comprising a support, a spring projected actuating bolt and a spring retracted latching bolt projectable from the same edge of and mounted on said support, an actuating lever pivoted on said support for operatively connecting said bolts together whereby as said actuating bolt is pushed back said latching bolt may be projected, a fulcrum at one side of the actuating lever and about which the actuating lever may be rocked, push means extending through the support opposite the other side of the actuating lever and adapted when pressed to engage the said other side of the actuating lever to rock it about the said fulcrum to break the operative connection between the two bolts and allow the projected latching bolt to retract, a fulcrum at the said other side of the actuating lever spaced from the aforementioned ful-

crum and about which the actuating lever may be rocked, push means extending through the support opposite the first mentioned side of the actuating lever and adapted when pressed to engage the said first mentioned side of the actuating lever to rock it about the second mentioned fulcrum to break the operative connection between the two bolts and allow the projected latching bolt to retract, the provision of two fulcrums 10 as aforesaid enabling the two push means on opposite sides of the actuating lever to be disposed co-axially.

ALBERT G. WHALLEY.
